Application February 20, 1934, Serial No. 712,148
In Great Britain March 23, 1933

5 Claims. (Cl. 19—1)

This invention relates to the manufacture of 5
yarns which are produced from threads of continuous
filaments but which have the appearance
and character of spun yarn made from staple
fibres.

In U. S. application S. No. 696,375 filed 2nd November, 1933 methods are described of converting 10
continuous filament threads directly into spun
yarns by passing such continuous filament
threads successively through at least two sets of
breaking rollers, which are rotated at successive-
ly higher peripheral speeds so as to subject the
filaments to a breaking tension and to convert
them into fibres, the fibrous material produced
15 being twisted according to this specification into
the final yarns (e. g. by ring or cap spinning de-
vices) as it proceeds from the breaking rollers.
In the conversion of filamentous material into
fibres in this manner, the length of each staple
20 fibre does not substantially exceed the distance
between the two sets of breaking rollers, and that
portion of the thread which lies between the
breaking rollers comprises a number of filaments
extending from one set of rollers to the other, and
25 in addition a number of filaments whose broken
ends lie between the two sets of rollers. The
filaments thus emerge from the last pair of
breaking rollers as a bundle of staple fibres which
is subsequently twisted to form a staple fibre yarn.

We have found that the certainty of the 30
operation and the uniformity of the product can be
much improved in such operation if the filaments
being treated are caused, during the application
of the breaking tension, viz. while they are pro-
35 ceeding from the first to the second set of break-
ing rollers, to pass through guiding means
adapted to confine them within a space which is
restricted laterally of the filaments so as to pre-
vent fibres falling away, and so as to direct the
40 filaments and fibres accurately to the second set
of rollers. In this way, the danger of the con-
tinuity of the filaments being broken is consid-
erably reduced, as also is the possibility of ir-
regularity in the filamentous thread. Further,
45 there is avoided the production of an excessive
number of free ends or "beard" in the twisted
yarn made from the broken material. This is of
especial significance when filaments of cellulose
acetate or other organic derivatives of cellulose
50 are concerned, since such materials are partic-
ularly liable to collect electric charges which
render them difficult to manage in loose fibrous
form and liable to separate from the main mass.
Conveniently, the guiding means may consist of a
55 tube through which the material passes, a slit

being provided if desired along the length of the
tube to facilitate threading.

One form of apparatus according to the invention
will now be described in greater detail with
reference to the accompanying drawing, in which 5

Fig. 1 illustrates the invention applied to fila-
ment-converting apparatus of the type described
in U. S. applications S. Nos. 696,374 and 696,375
filed 2nd November, 1933;

Fig. 2 is a plan view of a detail of Fig. 1 on 10
larger scale, while

Fig. 3 is an end elevation view of the detail
shown in Fig. 2.

Referring to Fig. 1, a plurality of continuous 15
filaments 5 are drawn from one or more pack-
ages, or other source of supply, (not shown),
by a pair of breaking rollers 6, 7 and proceed
through a further pair of breaking rollers 8, 9 to
a cap-spinning device 10 by way of a lappet 20
guide 11. The rollers 8, 9 rotate at a higher rate
than the rollers 6, 7 and stretch the continuous
filaments beyond their breaking point, the re-
sulting staple fibrous material 12 being twisted
by the cap-spinning device 10 and wound on a
bobbin 13. 25

A tube 14 horizontally disposed between the 30
two sets of rollers 6, 7 and 8, 9 surrounds the fila-
ments whilst they are being broken and provides
support for the filaments along almost the whole
of their run between the two sets of rollers. The 35
inside diameter of the tube is not greatly in ex-
cess of the diameter of the bundle of filaments
being treated, so that in addition to confining the
bundle within a relatively close area, and prevent-
ing loosened filaments dropping out of the body 40
of the bundle during the breaking operation, any
"whip" of the filaments, resulting from their rup-
ture under tension, is restrained.

In order to minimize the wear upon the respec- 45
tive pairs of rollers, the tube 14 is arranged to act
as a traversing guide for the filaments, and is at-
tached to a traversing rod 15 by means of a clamp
16 and screw 17, the traversing rod being recip-
rocated along the length of the rollers by eccen- 50
tric, cam, or like means (not shown). The ex-
tent of reciprocation of the rod 15 is governed in
accordance with the width of the rollers. Thus,
if the operative part of the rollers is, say, 4 inches
in length, the guide tube may be traversed over
a distance of 3 inches, i. e. to within $\frac{1}{2}$ inch of 55
each end of the operative part of the rollers.
Such distribution of wear is of especial impor-
tance when non-metallic or comparatively soft
materials are employed for the surfaces of the
rollers, for example when rollers of synthetic 60
fibres are used.

resins are employed as described in U. S. application S. No. 696,374.

The tube 14 and clamp 16 are slotted at 18 and 19 respectively, in order to facilitate threading of the filaments through the tube at the commencement of the breaking operation, the tube being suitably rounded at each extremity to allow of smooth entry and exit of the filaments.

Pressure between the two pairs of breaking rollers is maintained by a bridge-piece 20 which rides at its extremities on the axles 21, 22 of the rollers 7 and 9 respectively, the pressure being regulated by a bolt 23 and a nut 24, which may be housed in any of three apertures 25, 26, and 27 in the bridge-piece 20. The rollers may be of any desired length and may accommodate any suitable number of filamentous ends. The guide tubes for the several filamentous ends may conveniently be clamped to the same traversing rod 15.

The tube 14 is preferably formed of hard material such as steel, brass, glass, or porcelain in order to avoid undue wear or scoring of the interior of the tube by passage of the filaments therethrough, while the traversing rod 15 and clamp 16 may be made from any suitable metal. When the invention is carried out in connection with yarns which are liable to become electrified by friction with the working parts of the machine, as is the case with yarns of cellulose acetate or other organic derivative of cellulose, brass or porcelain guide tubes are found particularly suitable. Where a brass tube is used it is advisable to connect the tube to earth in order to assist in reducing the disadvantages arising from any charge which may be engendered upon the filaments. In this manner the handling of the filaments in the breaking and spinning operation is facilitated, and the filaments which are brought and maintained together in the form of a relatively compact thread of staple fibre have less tendency to spread out under electrical influences.

The staple fibrous end may be twisted directly by a high speed spinning device, as described and illustrated, or it may be treated as a roving and submitted to further passage between drawing rollers, either for the purpose of draughting or for further breakage or both, prior to spinning into a yarn. In this case also, the guide means according to the present invention may be employed. Any kind of continuous or substantially continuous filaments may be used, and particularly artificial filaments. While the invention may be applied to continuous artificial filaments of reconstituted cellulose such as viscose or cuprammonium filaments, it is especially convenient in connection with continuous filaments of cellulose acetate or other organic derivatives of cellulose referred to above. Examples of other organic derivatives of cellulose are other cellulose esters such as formate, propionate or buty-

rate and cellulose ethers such as ethyl or benzyl cellulose.

What we claim and desire to secure by Letters Patent is:—

1. Method of producing staple fibres from continuous filaments, comprising subjecting the filaments to a breaking tension and, along substantially the whole of that part of their length over which such tension is applied, confining the filaments within a space which is restricted laterally of the filaments so that they maintain substantially the same longitudinal position. 5

2. Method of producing staple fibres from continuous filaments of cellulose acetate, comprising subjecting the filaments to a breaking tension and, along substantially the whole of that part of their length over which such tension is applied, confining the filaments within a space which is restricted laterally of the filaments so that they maintain substantially the same longitudinal position. 15

3. Apparatus for producing staple fibres from continuous filaments, comprising pairs of nip rollers arranged in parallel relation and adapted to grip continuous filaments and subject them to a breaking tension, and a member disposed between one pair of nip rollers and the next, said member having a passage therein extending from a point near the nip of one pair of rollers to a point near the nip of the next pair of rollers and adapted to confine substantially the whole of the length of filaments passing from one pair of rollers to the next within a space which is restricted laterally of the filaments. 25

4. Apparatus for producing staple fibres from continuous filaments, comprising two pairs of nip rollers arranged in parallel relation and adapted to grip continuous filaments and subject them to a breaking tension, and a tube disposed between the two pairs of nip rollers and extending 40 from a point near the nip of the first pair of rollers to a point near the nip of the second pair of rollers so as to confine substantially the whole of the length of filaments passing from the first pair of rollers to the second pair within a space 45 which is restricted laterally of the filaments.

5. Apparatus for producing staple fibres from continuous filaments, comprising two pairs of nip rollers arranged in parallel relation and adapted to grip continuous filaments and subject them to a breaking tension, and a tube disposed between the two pairs of nip rollers and extending from a point near the nip of the first pair of rollers to a point near the nip of the second pair of rollers so as to confine substantially the whole 55 of the length of filaments passing from the first pair of rollers to the second pair within a space which is restricted laterally of the filaments, said tube being slotted along its length to allow of quick threading of the filaments there- 60 through.
